UNITED STATES PATENT OFFICE.

HORACE B. WORLEY, OF LAKE ARTHUR, NEW MEXICO.

KAFIR-CORN HEADER.

1,260,116.

Specification of Letters Patent. Patented Mar. 19, 1918.

Application filed July 3, 1917. Serial No. 178,404.

To all whom it may concern:

Be it known that I, HORACE B. WORLEY, a citizen of the United States, residing at Lake Arthur, in the county of Chaves and 5 State of New Mexico, have invented new and useful Improvements in Kafir-Corn Headers, of which the following is a specification.

This invention relates to machines for 10 heading Kafir corn, maize, cane and the like, and it has for its object to produce a machine of this class of simple and improved construction whereby the operation of heading may be expeditiously performed in a 15 labor saving manner.

A further object of the invention is to 20 produce a machine of the class described which in a simple and convenient manner may be adjusted to operate on stalks of different heights.

A further object of the invention is to 25 produce a machine of the class described having means whereby the detached heads may be loaded into a receptacle.

With these and other ends in view which 30 will readily appear as the nature of the invention is better understood, the same consists in the improved construction and novel arrangement and combination of parts 35 which will be hereinafter fully described and particularly pointed out in the claims.

In the accompanying drawings has been 40 illustrated a simple and preferred form of the invention, it being, however, understood that no limitation is necessarily made to the precise structural details therein exhibited, but that changes, alterations and modifications within the scope of the claims may be resorted to when desired.

In the drawings:

Figure 1 is a top plan view of a machine constructed in accordance with the invention.

Fig. 2 is a side elevation of the same.

Fig. 3 is a rear elevation.

Fig. 4 is a longitudinal sectional view.

Fig. 5 is a detail view partly in elevation and partly in section of the shaft 60 with its telescopic extension 61.

Fig. 6 is a perspective detail view of the notched plate 55.

Fig. 7 is a detail plan view of the cutting apparatus and related parts.

Fig. 8 is a detail plan view of the clutch 55 device C.

Fig. 9 is a sectional detail view taken on the line 9—9 in Fig. 8.

Corresponding parts in the several figures of the drawings are denoted by like characters of reference.

The axle of the improved machine comprises an arch 15 having spindles 16, 17 extending from the limbs thereof, said spindles carrying the ground wheels 18, 19. Supported on the spindles adjacent to the limbs 60 of the axle arch are boxes 20 each having a forwardly extending arm 21, said boxes being connected together by a yoke or arch 22 that extends rearwardly with respect to the axle arch 15 and the particular use of 70 which will be hereinafter set forth. The spindle 16 extends materially beyond the outer face of the ground wheel 18 and upon the projecting end of the spindle is pivotally mounted the tongue 23.

The gatherers G are each composed of an upper and a lower member 24, 25, said members converging in a forward direction, being 75 suitably secured together at their forward extremities while their rearward ends 80 are spaced apart by spacing members 26. The gathering members are also tapered in a forward direction, being beveled on their inner faces to facilitate the admission of stalks therebetween. The gatherers are 85 supported at their rearward ends on a cross bar 27 with which they are suitably connected, but through the greater portion of their length they are spaced apart, being connected together by arch members 28 se 90 cured on the top members 24 of the respective gatherers. The top and bottom members of the respective gatherers are provided with bearings wherein shafts 29, 30 are supported for rotation, said shafts being 95 supported adjacent to the inner edges of the top and bottom members of the gatherers. The shafts 29 are disposed intermediate the front and rear ends and the shafts 30 near the rearward ends of the respective gatherers. Trained over the shafts 29, 30 of each gatherer is a chain conveyer 100 31 some of the links of which are provided with prongs 32 adapted to engage the corn stalks for the purpose of feeding the same rearwardly between the gatherers. The rearward shafts 30 are extended above the top members 24 of the respective gatherers, one of said shafts being provided with a 105 sprocket wheel 33 and the other with a 110

gear wheel 34, the latter meshing with the gear wheel 35 on an idler shaft 36, the latter being also provided with a sprocket wheel 37 lying in the plane of the sprocket wheel 33 for the purpose of receiving motion and transmitting such motion in the proper direction to the shafts 30 by means to be presently described. The gatherers G are connected with the spindles 16, 17 by means of braces 38, said braces having boxes engaging the spindles and capable of turning freely thereon. Said gatherers are also provided on the lower faces of their bottom members 25 with lugs 39 which are connected by links 40 with the forwardly extending arms 21 of the boxes 20. The braces 38, it may be stated, are preferably connected with the gatherers by pivot members 41. Additional bracing and supporting members may be provided, one such member 42 being mounted at one end on one of the pivots 41 and having its other end securely connected with the tongue 23. Secured on the ground wheel 18, which also constitutes a bull wheel or traction wheel, is a clutch member C comprising a disk 43 and a sleeve 44, the latter surrounding the spindle. The spindle also carries a hub 45 on which is mounted a bevel gear 46 and a sprocket wheel 47, said hub having also a clutch member 48 mating with the clutch member C in the direction of which the hub is normally pressed by the action of a spring 49, one end of which abuts on the hub 45 while the other end of said spring abuts on one side member of a frame 50 which is mounted on the spindle, said frame being secured by means of a brace 51 which connects it with the tongue 23. The other side member of the frame 50 has an eye or boxing 52 engaging the sleeve 44 of the clutch member C. 53 is a lever having a forked head 54 receiving between the limbs thereof the sleeve 44 of the clutch member C, and also the clutch end of the hub 45, said forked head being cam-shaped as shown so that by rocking the lever, which extends rearwardly beneath the rear portion of the frame 50, in one direction, the hub 45 may be forced against the tension of the spring 49, thereby disengaging it from the clutch member C. By rocking the lever in the other direction, the hub will be released and will, by the tension of the spring 49, be forced in engagement with the clutch member 50. A notched plate 55 fixed on the under side of the rearward portion of the frame 50, serves to support the handle portion of the lever 53 and also to secure it in adjusted position by engagement with one of the notches 56 in the supporting plate.

Connected with one limb of the adjusting yoke 22 is a hand lever 57 having a stop member or locking device 58 engaging

a rack segment 59 which is fixed on the frame 50. By manipulating this lever, the frame 50 may be rocked, causing the forwardly extending arms 21 of the boxes 20 with which the yoke is connected to raise or lower the gathering members through the medium of the links 40, the parts being retained in adjusted position by means of the lock or stop member 58.

One of the gatherers G is provided with bearings for a substantially vertical shaft 60 which is provided below the gatherer with a telescopic extension 61 for which a suitable bearing 62 is provided, said telescopic extension carrying a bevel pinion 63 meshing with the bevel gear 46. The shaft 60 is provided intermediate the top and bottom members of the gatherer G in which it is supported with a crank 64 which is connected by a pitman 65 with a cutting member 66 supported for reciprocation on the bottom members of the two gatherers, and which co-operates with a stationary cutting member 67 which is likewise supported on the bottom members of the two gatherers in the path of the incoming stalks, the heads of which will be severed by the cutting apparatus when the machine is in operation. The shaft 60 is extended above the top member of the gatherer and carries a sprocket wheel 68 from which a chain 69 is trained over the sprocket wheels 33 and 37, thereby driving the chain conveyors, the cutting apparatus being actuated by the rotation of the shaft 60 as will be readily seen. The telescopic downward extension of the shaft permits the vertical adjustment of the gatherers by means of the adjusting lever 57, as previously described.

Hingedly connected with the cross bar 27, which supports the rearward ends of the gatherers, is an elevator 70, the conveyer of which is driven by a suitable transmission including a chain 71 which is trained over the sprocket wheel 47 on the hub 45. The free end of the elevator is supported by means of a brace bar 72 having its lower end mounted on the spindle 17 and provided near its upper end with a slot 73 for the passage of a bolt 74 that extends from the elevator frame and which is provided with a nut 75 which may be tightened to secure the elevator frame in adjusted position. A spring supported tightener or tightening pulley 76 is provided, which constantly engages the transmission chain 71 for the purpose of maintaining said chain under proper tension at all adjustments of the gathering members.

From the foregoing description, taken in connection with the drawings hereto annexed, the operation and advantages of this invention will be readily understood. The machine may be drawn by a team hitched to the tongue 23 adjacent to one side of the

machine. The gatherers may be adjusted to elevate down stalks and to guide the same, as well as the standing stalks, between the gatherers where they will be seized upon by 5 the chain conveyers, whereby they will be positively carried in engagement with the cutting apparatus whereby the heads will be severed and thrown on the elevator while the stalks pass beneath the axle arch 15 and 10 the yoke 22. The elevator may be adjusted to discharge into the box of a wagon following the machine, or into a suitable receptacle otherwise provided.

Having thus described the invention, 15 what is claimed as new is:

1. In a machine of the class described, an arched axle having elongated spindles, ground wheels on said spindles, a tongue mounted on one of said spindles adjacent to 20 the outer face of one of the ground wheels, boxes journaled on the spindles and having forwardly extending arms, a yoke connecting said boxes together, an adjusting lever connected with the yoke, a pair of gathering 25 members, braces connected pivotally with the gathering members and having boxes journaled on the spindles, lugs on the under faces of the gathering members, and links connecting said lugs with the forwardly ex- 30 tending arms of the boxes journaled on the spindles.

2. In a machine of the class described, an arched axle having elongated spindles, ground wheels on said spindles, a tongue 35 mounted on one of said spindles adjacent to the outer face of one of the ground wheels, boxes journaled on the spindles and having forwardly extending arms, a yoke connecting said boxes together, an adjusting lever connected with the yoke, a pair of gathering members, means for sup- 40 porting said gathering members above the axle, said means including brace members pivoted on the gathering members and having boxes receiving the spindles of the axle, links connecting the forwardly extending arms of the boxes journaled on the spindles with the gathering members, and means for securing the adjusting lever in position at various adjustments.

members, braces connected pivotally with the gathering members and having boxes journaled on the spindles, lugs on the under faces of the gathering members, and links connecting said lugs with the forwardly ex- 45 tending arms of the boxes journaled on the spindles, said gathering members having conveyer chains and cutting apparatus; in combination with means for transmitting motion to said conveyer chains and cutting 50 apparatus from one of the ground wheels, said means including a vertical crank shaft journaled in one of the gathering members and having a telescopic downward extension, a pinion on said extension, a bevel gear 55 mounted on one of the spindles in mesh with said pinion, means including a clutch device connecting said bevel gear operatively with one of the ground wheels, a pitman connecting the crank shaft with the cutting 60 apparatus, and a chain transmitting motion from the crank shaft to the chain conveyers.

3. In a machine of the class described, an arched axle having spindles, ground wheels on said spindles, boxes journaled on the 65 spindles and having forwardly extending arms, a yoke connecting said boxes together, an adjusting lever connected with the yoke, a pair of gathering members, means for sup- 70 porting said gathering members above the axle, said means including brace members pivoted on the gathering members and having boxes receiving the spindles of the axle, links connecting the forwardly extending arms of the boxes journaled on the spindles 75 with the gathering members, and means for securing the adjusting lever in position at various adjustments.

In testimony whereof I affix my signature.
HORACE B. WORLEY.
